2 Claims. (Cl. 91—411)

ABSTRACT OF THE DISCLOSURE

In a leveling apparatus, a plurality of cylindrical chambers, a piston rod reciprocally mounted in each of the chambers, a plurality of piston members mounted one on each of the piston rods and adapted to reciprocate therewith within the chambers, each of the piston members having first and second face portions, conduit means comprising a plurality of fluid conduits communicating the first face portion of one of the piston members with the second face portion of another of the piston members, one of the piston rods projecting axially outwardly from its associated chamber, an auxiliary chamber mounted coaxially of the associated chamber and having a control piston reciprocally disposed therewithin and connected to the projecting end of the one piston rod, a first actuating fluid disposed in the plurality of cylindrical chambers and adapted to be serially communicated through the fluid conduits, and a second actuating fluid in the auxiliary chamber adapted to effect reciprocation of the control piston, whereby the control piston will move axially within the auxiliary chamber and effect movement of the one piston rod which will in turn bias its associated piston member and thus serially communicate the first actuating fluid through the fluid conduits to cause the simultaneous movement in the same direction of the other of the piston members and piston rods.

This invention relates generally to foundry equipment and, more particularly, to a new and improved apparatus for transporting or conveying sand cores from a core loading fixture to a casting mold or flask preparatory to a casting operation.

In the manufacturing of a great many low tolerance cast metal, plastic and similar objects, it is of great importance, if not imperative, that the sand cores which are utilized be located as accurately as possible within the casting molds or flasks. This is particularly true when it is desired to obtain uniform size and shape of a plurality of objects being cast at the same time. Great care therefore, must be taken in the assembly of the cores so that they are initially oriented in precise relation and will remain in this relation as they are transferred from the core loading fixture and inserted into their respective positions within the casting mold. It is a primary object of the present invention, therefore, to provide a new and improved apparatus for conveying sand cores from a loading fixture to a casting mold which assures that the sand cores will remain in a preselected fixed orientation with respect to each other.

It is a more particular object of the present invention to provide a new and improved apparatus of the above character which includes means for assuring that the setting fixture used to convey the sand cores remains substantially level as it is moved toward and away from the loading fixture and casting mold.

It is yet a more particular object of the present invention to provide a new and improved apparatus of the above character which includes a plurality of legs reciprocally mounted on the setting fixture and adapted to bear against the upper end of the loading fixture and casting mold, all of said legs being concomitantly movable relative to the setting fixture for raising and lowering said fixture with

2

respect to the loading fixture or casting mold, thereby assuring that the setting fixture remains level as it picks up the sand cores from the loading fixture and deposits them within the casting mold.

It is still another object of the present invention to provide a new and improved apparatus of the above character which is adapted to be constructed of readily available component parts.

It is a further object of the present invention to provide a new and improved apparatus of the above character of a relatively simple design, which is easy to assemble and economical to commercially manufacture.

Other objects and advantages of the present invention will become apparent from the following detailed description taken in conjunction with the accompanying drawings, wherein:

FIGURE 1 is an elevated perspective view of an exemplary embodiment of the apparatus of the present invention shown in operative association with a conventional loading fixture and setting fixture;

FIGURE 2 is a top elevational view of the setting fixture assembly illustrated in FIGURE 1 and shows a portion of the exemplary embodiment of the present invention mounted thereon;

FIGURE 3 is an enlarged elevated perspective view of the control section of the leveling apparatus of the present invention; and

FIGURE 4 is a schematic representation of the leveling apparatus of the present invention.

Referring now to the drawings, a setting fixture leveling apparatus 10, in accordance with an exemplary embodiment of the present invention, is shown in operative association with a setting fixture assembly 12 and a loading fixture assembly 14, the former of which, preparatory to a casting operation, is adapted to be conveyed between the assembly 14 and an associated drag mold (not shown) to transfer to the drag mold one or more preformed sand cores 16 which, by way of example, are illustrated as the type used in casting V-type internal combustion engine blocks. The loading fixture assembly 14 comprises a suitable support structure 18 upon which a flat or planar support plate 20 is mounted. The plate 20 includes lug sections 22 for positioning a rectangular shaped housing section 24 which is open on the upper side and is thereby adapted to support the sand cores 16.

The setting fixture assembly 12 comprises a generally rectangular shaped body or housing 26 open on the lower end thereof for removably receiving the sand cores 16 from the upper end of the assembly section 24, as will hereinafter be described. The assembly 12 is adapted to be conveyed between positions above the assembly 14 and above the aforesaid drag mold by means of an overhead or elevated conveying system, such as a crane or the like (not shown), which comprises a vertically extending elevating cable 28 provided with a hook or similar attachment means 30 on the lower end thereof. The setting fixture housing 26 is secured to the cable 28 by having the attachment means 30 secured to a connecting ring or the like 32 which is mounted on the upper side of a laterally extending bar 34 that is spaced above and rigidly secured to the housing 26 by means of a pair of rods or shafts 36 and 38 which extend vertically upwardly from the opposite sides of the housing 26.

Means in the form of a plurality of retaining fingers 65 or the like, representatively illustrated in FIGURE 2 and generally designated by the numeral 40, are disposed within the housing 26 for releasably engaging the sand cores 16 when the setting fixture assembly 12 is oriented in a preselected manner with respect to the loading fixture assembly 14. The finger means 40 may be manually or automatically actuated in accordance with well known practices in the art, whereby to positively grip the sand cores

16 as the same are lifted out of the loading fixture assembly 14, and to positively release said cores when they are deposited within the associated drag mold.

As best seen in FIGURE 1, a pair of guide pins 42 and 44 are secured to and extend downwardly from the housing 26 at the opposite ends thereof, which pins 42, 44 are adapted to be removably received within guide apertures 46 formed within a pair of blocks 48 and 50 that are secured to and extend outwardly from the opposite ends of the loading fixture section 24, whereby to orient the setting fixture assembly 12 relative to the assembly 14 prior to the assembly 12 picking up the sand cores 16 from within the section 24. A suitable handle 51 is provided on one end of the housing 26 to facilitate manual positioning of the fixture assembly 12 relative to the assembly 14 preparatory to the assembly 12 being lowered toward the assembly 14.

In accordance with the principles of the present invention, the leveling apparatus 10 is provided on the setting fixture assembly 12 to assure that the housing 26 is maintained in a substantially level orientation when the same is lowered onto the top of the loading fixture assembly 14 and onto the top of the associated drag mold, whereby the setting fixture 12 will be oriented in the same relation with respect to the drag mold when it deposits the sand cores 16 therewithin, as it is with respect to the loading fixture 14 when the cores 16 are removed therefrom. Accordingly, the sand cores 16 will remain in the same precise relation they assume within the fixture 14 as they are conveyed to the drag mold and deposited therewithin preparatory to the casting operation.

Referring now in detail to the leveling apparatus 10 of the present invention, as best seen in FIGURES 1 and 2, the apparatus 10 comprises a plurality of piston and cylinder assemblies 52a, 52b, 52c and 52d, located one at each of the four corners of the housing 26. The assemblies 52a, 52b, 52c and 52d comprise hollow cylinders 54, 56, 58 and 60, respectively, each of which is closed at the upper and lower ends thereof by means of a pair of generally rectangular shaped end header members 62 and 64, respectively. The members 62, 64 of each of the assemblies 52 are rigidly secured on the opposite ends of their associated cylinders 54 through 60 by means of suitable longitudinally extending connecting rods 66 (see FIGURE 3), which extend between and are fixedly secured to the members 62 and 64 by suitable nuts or the like 68, as best seen in FIGURE 2. The assemblies 52 are preferably mounted within suitable recessed portions located at the corners of the housing 26, but alternatively, may be secured to the exterior sides of the housing 26 when the size or internal mechanisms (the core retaining fingers 40, etc.) of the setting fixture assembly 12 prevents mounting of the assemblies 52 within the housing 26. In either case, however, the assemblies 52 are located on the housing 26 in the same transverse or horizontal plane and are arranged such that each overlies a portion of the upper edge 70 of the loading fixture section 24 when the setting fixture assembly 12 is disposed in the position in which the sand cores 16 are picked up from the assembly 14. Also, the assemblies 52 are located on the housing 26 at a position such that they overlie a common horizontal surface or support structure (not shown) adjacent or upon the drag mold in which the sand cores 16 are deposited by the setting fixture assembly 12.

As best seen in FIGURE 4, the cylinders 54, 56 and 58 are provided with transversely extending partitions 72, 74 and 76, respectively, which divide the interior of these cylinders into upper and lower chambers or compartments 78 and 80, respectively. Disposed within each of the chambers 80 is a suitable hydraulic piston 82 which is movable or reciprocal between the lower sides of the partitions 72, 74 and 76, and the upper sides of the header members 64 closing the lower ends of the cylinders 54, 56 and 58, in response to the changes in the fluid or hydraulic pressure within the chambers 80, as will later be

described. An identical type piston 84 is reciprocally mounted within the cylinder 60 and is adapted to cooperate with the pistons 82 during operation of the apparatus 10, in a manner later to be described.

The piston and cylinder assemblies 52a, 52b, 52c and 52d include piston rods 86, 88, 90 and 92, respectively, which extend coaxially through the cylinders 54, 56, 58 and 60, and are fixedly secured to the respective pistons 82 and 84, so that reciprocation of the pistons 82 and 84 will effect reciprocal movement of the piston rods 86 through 92 in the conventional manner. The upper ends of the piston rods 86, 88 and 90 extend upwardly through fluid-tight openings in the partitions 72, 74 and 76 and through suitable openings in header members 62 of the cylinders 54, 56 and 58. A plurality of helical coil springs 94 may be disposed one in each of chambers 78 coaxially of the upper ends of the piston rods 86, 88 and 90 to help offset the weight of the assembly 12 and thereby reduce the effort required to elevate the assembly 12 off of the assembly 14 and drag mold, as will later be described. The lower ends of the springs 94 bear upon suitable radially outwardly extending snap rings or the like 96 secured to the piston rods 86, 88 and 90 directly above the partitions 72, 74 and 76, while the upper ends of the springs 94 bear against the lower sides of the upper header members 62 closing the upper ends of the cylinders 54, 56 and 58. With this arrangement, the piston rods 86, 88 and 90 are normally urged downwardly relative to the cylinders 54, 56 and 58 such that when the piston rods 86, 88 and 90 move upwardly relative to their respective cylinders, they must do so against resistance of the coil springs 94.

The lower ends of the piston rods 86, 88, 90 and 92 extend downwardly from the cylinders 54 through 60 and are adapted to act as leveling legs in controlling the attitude or orientation of the setting fixture assembly 12 relative to the loading fixture assembly 14, as will later be described in connection with the operation of the apparatus 10 of the present invention. The lower ends of the piston rods 86 through 92 are adapted to bear upon the upper edge 70 of the loading fixture section 24 to assure that the setting fixture assembly 12 is substantially level prior to and during the time the sand cores 16 are picked out of the assembly 14. Accordingly, the lower ends of the piston rods 86 through 92 are provided with enlarged diameter end caps or "feet" 98 (see FIGURE 1), which are adapted to provide a positive and firm support for the setting fixture assembly 12 as it is lowered upon the loading fixture assembly 14.

Referring now to the schematic representation of the apparatus 10 of the present invention shown in FIGURE 4, it will be seen that the piston and cylinder assemblies 52a, 52b, 52c and 52d are serially connected by means of a plurality of hydraulic conduit means. More particularly, the portion of the cylinder 60 interjacent the lower side of the piston 84 and the lower header member 64 is connected by a suitable conduit 100 with the portion of the cylinder 58 interjacent the partition 76 and the upper side of the piston 82. In a similar manner, the portion of the cylinder 58 interjacent the lower side of the piston 82 and the lower header member 64 is connected by a conduit 102 with the portion of the cylinder 56 interjacent the upper side of the piston 82 and the lower side of the partition 74. Likewise, the portion of the cylinder 56 interjacent the lower side of a piston 82 and the upper side of the associated header member 64 is connected by a conduit 104 with the portion of the cylinder 54 interjacent the partition 72 and the upper side of the associated piston 82. The portion of the compartment 80 in the cylinder 54 interjacent the lower side of the piston 82 and the upper side of the header member 64 is connected by means of a suitable conduit 106 with the portion of the cylinder 60 interjacent the top of the piston 84 and the lower side of the header member 62. The conduits 100, 102, 104, and 106 are connected by suitable conduits 108,

110, 112, 114 and 116 with a fluid reservoir, representatively illustrated in FIGURE 4 and designated by the numeral 118. Suitable valve means, generally designated 120, are disposed in the conduits 108, 110, 112 and 114 and adapted to be selectively opened to facilitate purging the hydraulic circuit.

As best seen in FIGURES 3 and 4, mounted on the top of the piston and cylinder assembly 52d is a control assembly, generally designated 122. The assembly 122 is essentially a piston and cylinder assembly and comprises a cylinder 124 which is closed on the upper and lower ends thereof by suitable header members 126 and 128, respectively. The header members 126 and 128 are rigidly secured to the cylinder 124 by suitable connecting rods 130 that extend between and are rigidly secured to the header members 126 and 128 by means of suitable nuts or the like 132 (see FIGURE 3). The lower header member 128 is secured to the top of an upper header member 62 of the assembly 52d in a manner such that the cylinder 124 is coaxially aligned with the cylinder 60. The upper end of the piston rod 92 extends upwardly through the header members 62 and 128 into the interior of the cylinder 124 and is rigidly connected to a piston 134 which is disposed within the cylinder 124 and adapted to reciprocate simultaneously with the piston rod 92 and piston 84. More particularly, the piston 134 is adapted to move upwardly and downwardly within the cylinder 124 in response to variations in pneumatic pressure within the cylinder 124, and thereby bias the piston rod 92 and piston 84 upwardly and downwardly within the cylinder 60. A mounting plate 136 is secured to one side of the assembly 122 by suitable screws, bolts or the like 138 and is adapted to support a combination control handle and valve device, generally designated by the numeral 140. The device 140 comprises an inlet section 142 which is communicable with a source of pressurized air, as is commonly available in foundries and the like, by means of a suitable inlet conduit 144. A control handle 146 is movably mounted on the top of the device 140 and is adapted to control the flow of air between either of two outlet conduits 148 or 150 which are communicable with the air inlet section 142 and the portions of the cylinder 124 located above and below the piston 134. With this arrangement, when the handle 146 is disposed in a pre-selected position, pressurized air is communicated into the device 140 and thereafter transmitted to the top of the cylinder 124 through the conduit 148, whereby the piston 134, piston rod 92 and piston 84 will move downwardly within the respective cylinders 124 and 60. Conversely, when the handle 146 is disposed in another preselected position, pressurized air will be communicated from the section 142 into the lower end of the cylinder 124 through the conduit 150, whereby the piston 134 will move upwardly within the cylinder 124, thereby biasing the piston rod 92 and piston 84 upwardly within the cylinder 60.

To facilitate correlating the various hereinabove described component parts of the leveling apparatus 10 of the present invention, a brief exemplary operational cycle thereof will now be described in detail, with particular reference being made to the schematic diagram illustrated in FIGURE 4.

Assuming that the inlet conduit 144 is connected to a source of pressurized air, at such time as it is desired to convey the sand cores 16 from the loading fixture assembly 14 to a predetermined location, for example, to the drag mold or the like, the setting fixture assembly 12 is moved by means of the aforementioned conveying means to a position directly above the loading fixture assembly 14. The assembly 12 is then lowered onto the upper edge 70 of the assembly section 24, with the guide pins 42 and 44 inserted within the apertures 46 formed in the blocks 48 and 50 that are secured to the opposite ends of the section 24. Assuming that the retaining fingers 40 are disposed in a position where they will not engage the sand cores 16 as the setting fixture assembly 12 is lowered

further with respect to the assembly 14, the control handle 146 is biased to the position permitting pressurized air to flow through the conduit 150 and into the lower end of the cylinder 124, whereby the piston 134, piston rod 92 and piston 84 will move upwardly within the respective cylinders 124 and 60. As the piston 84 thus moves within the cylinder 60, the hydraulic fluid interjacent the upper side of the piston 84 and the upper header member 62 is forced through the conduit 106 into the portion of the cylinder 54 interjacent the lower side of the piston 82 and the lower header member 64, resulting in the piston 82 and piston rod 86 moving upwardly with respect to the cylinder 54. As will be apparent, the hydraulic fluid interjacent the upper side of the piston 82 and the partition 72 is forced through the conduit 104 into the portion of the cylinder 56 interjacent the lower side of the piston member 82 and the associated lower header member 64, thereby causing the piston member 82 and the piston rod member 88 to move upwardly with respect to the cylinder 56. Similarly, the fluid within the cylinder 56 is forced through the conduit 102 into the portion of the cylinder 58 directly below the piston 82, thereby causing the member 82 and the piston rod 90 to move upwardly with respect to the cylinder 58. By virtue of the fact that the hydraulic circuit is closed, all of the piston rod members 86, 88, 90 and 92 will move upwardly concomitantly to the positions indicated by the phantom lines in FIGURE 1, and thereby lower the assembly 12 toward the upper edge 70 of the assembly section 24 while maintaining the assembly 12 in a substantially level attitude with respect to the loading fixture 14.

After the assembly 12 has been thus lowered, the retaining fingers 40 may be actuated to engage the sand cores 16 disposed within the loading fixture assembly 14, and the assembly 12 is raised off the top of the assembly 14 by biasing the control handle 146 to the position communicating pressurized air through the conduit 148 and into the upper end of the cylinder 124, thereby biasing the piston member 134, piston rod 92 and piston member 84 downwardly with respect to the cylinders 124 and 60. As the piston member 84 thus moves, the hydraulic fluid in the cylinder 60 interjacent the lower side of the piston member 84 and the lower header member 64 is forced through the conduit 100 into the cylinder 58 above the piston member 82, thereby biasing the member 82 and piston rod 90 downwardly with respect to the cylinder 58. The hydraulic fluid within the lower end of the cylinder 58 is then serially forced through the conduit 102, and the hydraulic fluid within the lower end of the cylinder 56 is serially forced through the conduit 104 to bias the piston rod members 88 and 86 downwardly with respect to the cylinders 56 and 58, as will be apparent. Accordingly, all of the piston rod members 86, 88, 90 and 92 are simultaneously moved downwardly with respect to the setting fixture assembly 12, thereby causing the assembly 12 to be elevated in a level orientation so that the sand cores 16 are maintained in their respective preselected positions. At this time, the conveying means may be properly energized to further elevate the fixture assembly 12 with the sand cores 16 releasably secured thereto and convey the same to a position located above the drag mold into which the sand cores 16 are to be placed.

The entire assembly 12 is then lowered onto the top of the drag mold until the end caps 98 rest upon the support structure adjacent the mold, at which time the control handle 146 is biased to the position permitting pressurized air to flow into the lower end of the cylinder 124, resulting in the piston rod members 86, 88, 90, 92 simultaneously moving upwardly to effect lowering of the assembly 12 with respect to the drag mold. It will be seen that as the assembly 12 is lowered, it will maintain the same level attitude it assumed during the time the sand cores 16 were being picked up from the load-

ing fixture assembly 14. Accordingly, the sand cores 16 will remain in the same precise relation with respect to each other and with respect to the assembly section 24 as they are conveyed to the drag mold and inserted there-within preparatory to the casting operation. After the assembly 12 has been lowered by the leveling apparatus 10, the retaining fingers 40 may be actuated to release the sand cores 16 within the drag mold. The control handle 146 may then be biased to the above described position where the piston rod members 86, 88, 90 and 92 move downwardly with respect to the assembly 12, thereby elevating the assembly 12 off the assembly 14 to prevent the retaining fingers 40 or any other structural portions of the assembly 12 from engaging the sand cores 16 as the assembly 12 is moved away from the mold. The conveying means may then be employed to transport the setting fixture assembly 12 back to a position overlying the same or another loading fixture assembly 14 to pick up another set of the sand cores 16 to initiate the next operational cycle of the assembly 12 and the leveling apparatus 10 of the present invention.

While it will be apparent that the exemplary embodiment herein illustrated is well calculated to fulfill the objects stated, it will be appreciated that the leveling apparatus 10 of the present invention is susceptible to modification, variation and change without departing from the proper scope or fair meaning of the subjoined claims.

What is claimed is:

1. In a leveling apparatus, a plurality of cylindrical chambers, a piston rod reciprocally mounted in each of said chambers, a plurality of piston members mounted one on each of said piston rods and adapted to reciprocate therewith within said chambers, each of said piston members having first and second face portions, conduit means comprising a plurality of fluid conduits communicating the first face portion of one of said piston members with the second face portion of another of said piston members,

5
10
15
20

one of said piston rods projecting axially outwardly from its associated chamber, an auxiliary chamber mounted coaxially of the said associated chamber and having a control piston reciprocally disposed therewithin and connected to the projecting end of said one piston rod, a first actuating fluid disposed in said plurality of cylindrical chambers and adapted to be serially communicated through said fluid conduits, and a second actuating fluid in said auxiliary chamber adapted to effect reciprocation of said control piston, whereby said control piston will move axially within said auxiliary chamber and effect movement of said one piston rod which will in turn bias its associated piston member and thus serially communicate said first actuating fluid through said fluid conduits to cause the simultaneous movement in the same direction of the other of said piston members and piston rods.

2. The invention as set forth in claim 1 which comprises a fixedly mounted loading fixture and a transportable setting fixture, wherein said plurality of cylindrical chambers are fixedly secured to said setting fixture, and wherein said piston rods project downwardly from said setting fixture and are adapted to bear against the upper side of said loading fixture, whereupon simultaneous movement of said piston members will effect level movement of said setting fixture toward or away from said loading fixture.
